UNITED STATES PATENT OFFICE.

HENRY THOMPSON, OF ROCKLAND, MAINE, ASSIGNOR TO HIMSELF, D. C. HASKELL, AND C. H. HASKELL, OF SAME PLACE.

IMPROVEMENT IN RIGGING-STOPPERS.

Specification forming part of Letters Patent No. 55,789, dated June 19, 1866.

To all whom it may concern:

Be it known that I, HENRY THOMPSON, of Rockland, in the county of Knox and State of Maine, have invented a new and useful Rigging-Stopper; and I do hereby declare the same to be fully described in the following specification and represented in the accompanying drawings, of which—

Figure 1 is a side view, and Fig. 2 an edge elevation, of it. Figs. 3 and 4 are views of the pair of its jaws.

In some respects it is like an ordinary vise provided with a handle, although in others it differs materially from such vise. It has two jaw-levers, A B, one of which is made to project from a handle, C, and has the other jaw-lever hinged to it, as shown at D. The jaws of these levers, which are exhibited in the drawings, are to be so formed as to fit to a rope—that is, they are to be provided with helix-grooves *a a a b b b*—whereby, when they are made to grasp the setting-up rope, which runs through the dead-eyes of the strands of a vessel, they may fit to its strands, and thus be prevented from slipping on the rope.

A spring, E, arranged between the two jaw-levers and fastened to one of them, serves to move the other in a direction away from the first, so as to open the jaws.

A toothed rack, F, is formed on the movable jaw-lever, and engages with a toothed sector,

G, affixed to another lever, H, whose fulcrum *f* is supported by two arms, I I, which are arranged on opposite sides of the two jaw-levers and turn on a common fulcrum-pin, *g*, going through the stationary jaw-lever.

The toothed sector and its lever are for closing the jaws and holding them closed upon a rope, the arms admitting of the adjustment of the sector in the rack—that is, higher or lower therein—as circumstances may require.

The said instrument or rigging-stopper is designed to be used to prevent the straining-rope roven through the dead-eyes from slipping back after it has been drawn tight by a tackle or other means, and for this purpose the rigging-stopper is to be made to grasp the rope close to a dead-eye and to hold such rope firmly while its end is being secured or fastened.

I claim as my invention—

The rigging-stopper, made and for use substantially as hereinbefore described—that is to say, of the toothed sectoral lever, the rack, and the movable supporting-arm and the two jawed levers, arranged and applied together in manner and so as to operate as explained.

HENRY THOMPSON.
